BLOOD WARMING APPARATUS

Wayne M. Hultberg, Glenview, Ill., assignor to Baxter
Laboratories, Inc., Morton Grove, Ill.

Filed Aug. 12, 1970, Ser. No. 24,440

Term of patent 14 years

Int. Cl. D24—02

U.S. Cl. D83—1

FIG. 1 is a perspective view of a blood warming apparatus, showing my new design;

FIG. 2 is a front elevational view of the apparatus of FIG. 1;

FIG. 3 is a left side elevational view of the apparatus of FIG. 1;

FIG. 4 is a rear elevational view of the same apparatus; FIG. 5 is a top plan view of the apparatus of FIG. 1.

I claim:

The ornamental design for a blood warming apparatus, substantially as shown.
